[57] CLAIM

The ornamental design for a binder, as shown and described.

DESCRIPTION

FIG. 1 is a front perspective view of a binder showing my new design in a closed position;

FIG. 2 is a top plan view thereof, the undisclosed bottom being the same;

FIG. 3 is a rear perspective view thereof, in a partially opened position;

FIG. 4 is a reduced scale end elevational view thereof, in a fully opened position, the undisclosed end being the same;

FIG. 5 is a top plan view thereof in a fully opened position, the undisclosed bottom being the same;

FIG. 6 is a front perspective view thereof, in a partially opened position;

FIG. 7 is an enlarged front elevational view of a portion of the spine element thereof, in a fully opened position; and,

FIG. 8 is a bottom plan view of FIG. 7.

FIG. 1

FIG. 2

FIG. 3
